Patented Apr. 17, 1917.

UNITED STATES PATENT OFFICE.

JOHN W. TROXELL, OF ROBY, ILLINOIS.

HOLDING DEVICE FOR LIVE STOCK.

1,223,126.

Specification of Letters Patent. Patented Apr. 17, 1917.

Application filed December 4, 1916. Serial No. 134,904.

To all whom it may concern:

Be it known that I, JOHN W. TROXELL, a citizen of the United States, and a resident of Roby, in the county of Christian and State of Illinois, (post-office address Breckenridge, Sangamon county, Illinois,) have invented a new and Improved Holding Device for Live Stock, of which the following is a full, clear, and exact description.

10 My invention relates to a structure adapted to be positioned in an opening through a fence, in a doorway or other situation and adapted to hold live stock while being dehorned, branded, or in ringing or snouting 15 hogs, or vaccinating stock, or performing other operations thereon.

The prime object of the invention is to provide a structure for the indicated purpose that can be operated with facility to 20 grip or release the stock and will effectively hold the stock.

A more specific object of the invention is to provide a device of the indicated purpose of strong and simple construction.

25 The nature of the invention and its advantages will appear as the description proceeds.

Reference is to be had to the accompanying drawings forming part of this specification in which similar reference characters indicate corresponding parts in all the views.

Figure 1 is a front view of a stock-holding device embodying my invention;

Fig. 2 is a horizontal section on the line 35 2—2, Fig. 1;

Fig. 3 is a transverse vertical section on the line 3—3, Fig. 1.

In carrying out my invention suitable frame members or supporting elements are 40 provided. In the illustrated example a base 10 is formed of spaced bars as shown best in Fig. 3 and rising from the same at the sides are standards 11, the upper portions of which are formed of spaced members 11^a.

45 The standards 11 at one side rise higher than those at the other side and to the shorter of the standards a hand lever 12 is fulcrumed at one end as at 13. The opposite end of the lever is received between the adjacent spaced standard members 11^a, which latter receive between their upper ends a spacing block 11^b which is secured in position by a bolt or rivet 14. The lever may be held in a given position by a pin 15

50 which is insertible optionally in any one of a vertical series of transverse pin holes 11^c

in the adjacent standard members 11^a. Vertical stock-holding bars 16 are provided to be moved toward and from each other by the operation of the hand lever 12, the means in the illustrated example provided for the purpose consisting of vertically disposed levers 17 outside of the holding bars 16, said vertical levers being connected at their upper ends with the lever 12 by 60 toggle links 18, the convergent upper ends of which are pivoted as at 19 to the lever 12, while the lower ends of the toggle links are pivotally connected as at 20 to the respective vertical levers 17. The levers 17 are 65 fulcrumed between their ends as at 21 between cross bars 22 secured to the standards 11 at the base of the spaced standards 11^a. In order to effect a connection between the holding bars 16 at their lower ends and the 70 levers 17, links 23 may be employed, said links being connected respectively as at 24 and 25 to the said levers 17 and the said bars 16. At the upper ends the bars 16 are connected with the vertical levers 17 through 75 the medium of straps 25; one set of straps 25 are pivotally connected at one end to one vertical lever 17 as at 26, the opposite ends of said straps being connected to the holding bar 16 at the opposite side of the structure. 80 Thus, connections are established between each lever bar 17 and the opposite holding bar 16.

By the described construction the operation of the lever 12 gives substantially a 90 parallel movement to the holding bars 16 toward and from each other as indicated in dotted lines Fig. 1 in which the lever 12 is indicated in the lowered position, while the vertical levers 17 are rocked to an inclined position, the holding bars having been thus moved to an inner position to 95 embrace the neck of the animal.

The vertical levers 17 and the holding bars 16 are firmly braced by reason of the 100 lower ends thereof having guided movement between the spaced base members 10 which provide a slot accommodating said vertical levers and holding bars. The dimensions of the elements entering into the structure may 105 be such as to accommodate the largest or the smallest animal that will be required to be held.

By the employment of the straps 25 arranged as shown, the upper ends of the holding bars 16 are positively drawn together. 110 On the other hand the links 23 cause the

holding bars to be forced together at their lower ends without presenting any obstruction between the bars other than the base 10 which offers no material obstruction.

5 I wish to state in conclusion that although the illustrated example constitutes a practical embodiment of my invention, I do not limit myself strictly to the mechanical details herein illustrated, since manifestly the 10 same can be considerably varied without departure from the spirit of the invention as defined in the appended claims.

Having thus described my invention I claim as new, and desire to secure by Letters Patent:

1. A holding device for live stock, including a supporting structure, approximately upright holding bars movable in said structure toward or from each other to grip 20 or release an animal, upright levers disposed outside of said holding bars and fulcrumed between their ends to rock on horizontal axes, connections between each of said levers at the upper end thereof and the 25 upper end of the opposite holding bar, means at the base of the structure with which the lower ends of said levers are afforded guided movement, means forming a

direct connection between each lever at the lower end and the holding bar adjacent thereto, and means to actuate said levers.

2. A holding device for live stock, including a supporting structure, approximately upright holding bars movable in said structure toward or from each other to grip or release an animal, approximately upright levers disposed in said structure outside of said holding bars and fulcrumed between their ends to rock on a horizontal axis, connections between each of said levers at the upper end thereof and the opposite holding bar, means forming a direct connection between each lever at the lower end and the holding bar adjacent thereto, the said levers and bars having guided movement at their lower ends in the said structure, a hand lever above the holding bars and fulcrumed at one end on said structure at one side of the latter, means to adjustably hold the lever at the opposite side of said structure, and links connected with said hand lever between its ends and diverging therefrom, the lower ends of the links being pivotally secured to the upper ends of the first-mentioned levers.

JOHN W. TROXELL.
